UNITED STATES PATENT OFFICE.

ELLIS W. TEST, OF MICHIGAN CITY, INDIANA, ASSIGNOR TO HASKELL & BARBER CAR CO., INC., A CORPORATION OF NEW YORK.

CAR-BOLSTER.

1,265,401.

Specification of Letters Patent.

Patented May 7, 1918.

Application filed January 12, 1918. Serial No. 211,549.

To all whom it may concern:

Be it known that I, ELLIS W. TEST, a citizen of the United States, and resident of Michigan City, county of Laporte, and State 5 of Indiana, have invented certain new and useful Improvements in Car-Bolsters, of which the following is a specification, and which are illustrated in the accompanying drawings, forming a part thereof.

10 The invention relates to improvements in bolsters for railroad cars. Bolsters are preferably formed relatively deep adjacent their center and tapering toward the ends to provide sufficient clearance for other parts, as 15 well as eliminate unnecessary weight and material.

One of the objects of this invention is to provide means for readily constructing such a bolster from channel members and plates 20 of uniform cross-section, and at the same time provide adequate support for the side body bearings connected to the under side of the bolster.

One embodiment of the invention is illustrated in the accompanying drawings, in which—

Figure 1 is a side elevation, one half in section, of a bolster embodying the features of this invention;

30 Fig. 2 is a plan view of the bolster, a portion being broken away;

Fig. 3 is a section on the line 3—3 of Fig. 1; and

Fig. 4 is a perspective view of one of the 35 parts of the bolster.

The bolster shown in the drawings comprises two channels 10, each having a central web 11 and upper and lower flanges 12 and 13. The flanges of each pair of channels are 40 arranged in opposite directions, and are riveted to upper and lower plates 14, 15.

Since the channels 10 are of uniform cross-section and preferably the bolster should taper adjacent its ends, the end portions of the lower flanges 13 and part of the central web 11 of each channel is cut away and replaced by an angle piece 16. One flange 17 of the angle piece is connected to the central web 11 of the channel, 50 while the other flange 18 projects laterally and is inclined upwardly toward the end of the bolster. The flange 18 is riveted to the lower plate 15.

To the under side of the plate 15 and 55 angle piece 16 is attached a side body bear-

ing block 19, and to strengthen the bolster at that point ribs 20 are provided between the flanges 17 and 18 immediately above the side bearing block.

As the flange 17 of the angle piece is riveted to the inner face of the web 11, it is necessary to cut away much more of the web than is required to produce the tapered end to the bolster in order to give room for the ribs 20. Consequently the piece cut away 60 from each end of each channel is substantially rectangular to provide ample room for the ribs 20. The corner 21 of this cut away portion 22 is preferably rounded to avoid the development of cracks.

70 Each flange 17 is formed with an offset portion 23 of the same configuration as the cut away part 22, so that the edge of the latter is in substantial engagement with the outer edge of the offset portion, and the 75 offset portion 23 is in substantially the same plane as the web 11.

The angle pieces are formed with end plates or flanges 24, adapted to close the end of the central passage through the bolster as 80 well as extend between the projecting flanges of the angle piece and channel. The top and bottom plates 14 and 15 are centrally apertured to receive the king bolt, and a socket block 25 for this bolt is arranged 85 within the bolster.

I claim as my invention—

1. A body bolster of box form having lateral outwardly directed flanges adjacent its top and bottom, the lower part of the side 90 members of the bolster being cut away adjacent each end, angle members having one flange attached to the sides of the bolster adjacent said cut away portions, said flange decreasing in width toward the ends of the 95 bolster, the other flange of said angle members being inclined upwardly toward the end of the bolster, and reinforcing ribs between the flanges of said angle members, the edge of said cut-away portions being spaced 100 apart from said last-mentioned flanges adjacent the reinforcing ribs to allow said ribs to extend under said edges.

2. A body bolster of box form having lateral outwardly directed flanges adjacent its 105 top and bottom, the lower part of the side members of the bolster being cut away adjacent each end, angle members having one flange attached to the inner face of the side walls of the bolster adjacent said cut away 110

portions, the other flange of said angle members being inclined upwardly toward the end of the bolster, a body side bearing block secured to the under side of said angle members, and reinforcing ribs between the flanges of said angle members above said bearing.

3. A body bolster of box form having lateral outwardly directed flanges adjacent its top and bottom, the lower part of the side members of the bolster being cut away adjacent each end, angle members having one

flange attached to the sides of the bolster adjacent said cut away portions, the other flange of said angle members being inclined upwardly toward the end of the bolster, said first-mentioned flange of the angle member being offset between the edge of said cut away portion and said second flange of the angle member whereby said offset portion forms a substantial continuation of the side of the bolster. 15 20

ELLIS W. TEST.

Copies of this patent may be obtained for five cents each. by addressing the "Commissioner of Patents, Washington, D. C."

It is hereby certified that the assignee in Letters Patent No. 1,265,401, granted May 7, 1918, upon the application of Ellis W. Test, of Michigan City, Indiana, for an improvement in "Car-Bolsters," was erroneously described and specified as "Haskell & Barber Car Co., Inc.," whereas said assignee should have been described and specified as *Haskell & Barker Car Co., Inc.*, as shown by the records of assignments in this office; and that the said Letters Patent should be read with this correction therein that the same may conform to the record of the case in the Patent Office.

Signed and sealed this 28th day of May, A. D., 1918.

[SEAL.]

R. F. WHITEHEAD,

Acting Commissioner of Patents.

Cl. 105—103.
